CLAIM

The ornamental design for a tattoo machine, as shown and described.

DESCRIPTION

FIG. 1 is a front skewed perspective view of a tattoo machine in accordance with the present invention;

FIG. 2 is a bottom view thereof;

FIG. 3 is a top view thereof;

FIG. 4 is a left side view thereof;

FIG. 5 is a right side view thereof;

FIG. 6 is a front view thereof; and,

FIG. 7 is a rear view thereof.

The features shown in dashed lines in the various Figures are for illustrating environmental structure and form no part of the claimed design.

1 Claim, 4 Drawing Sheets
